UNITED STATES PATENT OFFICE.

FRANCISCO ESPAILLAT DE LA MOTA, OF LA VEGA, DOMINICAN REPUBLIC.

CIGAR AND METHOD OF MAKING THE SAME.

Application filed May 10, 1920. Serial No. 380,335.

To all whom it may concern:

Be it known that I, FRANCISCO ESPAILLAT DE LA MOTA, citizen of the Dominican Republic, residing at La Vega, Province of La Vega, Dominican Republic, have invented certain new and useful Improvements in Cigars and Methods of Making the Same, of which the following is a specification.

This invention has as one of its objects to 10 evolve a novel method by which cigars may be manufactured more economically and which will permit of the use of a filling of small pieces of tobacco such as ordinarily can only be used in cigarettes and pipes. 15 Another object of the invention is to evolve a method of manufacturing cigars certain of the steps of which method may be carried out by machinery not materially different from that employed in the manufacture 20 of cigarettes, thus further reducing the cost of manufacture.

The invention also has as its object to produce a cigar which will possess identically the appearance of a hand made cigar 25 having a long filler and which will in every way be as satisfactory an article as a long filler cigar and which will yet be much less expensive to manufacture.

In the accompanying drawings:

30 Figure 1 is a perspective view illustrating the body or filler of the cigar as produced by the first step of the method;

Fig. 2 is a vertical longitudinal sectional view thereof, the body or filler having been 35 subjected to a succeeding step;

Fig. 3 is a perspective view illustrating a further step;

Fig. 4 is a vertical longitudinal sectional view through the partly finished cigar at the 40 completion of the step shown in Fig. 3;

Fig. 5 is a view similar to Fig. 3 illustrating the final step of the method;

Fig. 6 is a view partly in longitudinal section and partly in elevation illustrating 45 the completed cigar.

In carrying out the method, I first prepare what is to constitute the body or filler of the cigar and in this step I may make use of any approved type of cigarette making machine although it will be necessary to repropportion the mold parts thereof so that the machine will be adapted to produce what is the equivalent of a large-size cigarette, this product in fact being of substantially the same diameter and length as the cigar which is to be manufactured. As

a filler proper, I may employ tobacco cut in fine strips or shreds and known in the trade as fine cut tobacco, or I may employ tobacco cut into small pieces or flakes and in no respect different from tobacco commonly employed in pipes and in rolling cigarettes, or, if desired, I may employ a mixture of these two kinds of tobacco, but in any event the filler proper will consist 60 of small pieces of tobacco as distinguished from long leaf portions such as are employed in the manufacture of the type of cigars known as long-filler cigars. This 65 filler is fed into the cigarette making machine and the machine is operated to produce an oversize cigarette which is clearly 70 shown particularly in Figs 1 and 2 of the drawings, the filler proper being indicated by the numeral 1 and the paper wrapper by 75 the numeral 2 and this wrapper being sealed as is usual in the manufacture of cigarettes. As stated this product is to be of a diameter 80 and length substantially equal to the diameter and length of the cigar to be manufactured.

The next step in the method is performed by a workman who by hand removes from one end of the product shown in Figs. 1 and 2 of the drawings, a suitable quantity of 85 the filler 1 so that the filler at this end of the product is less compact than throughout the remainder of the length of the product. The end thus treated is indicated in the drawings by the numeral 3.

Next, the product shown in Figs. 1 and 2 is wrapped by hand with a wrapping 4 of 90 leaf tobacco of a fair quality in the same manner as the long filler of an ordinary cigar is wrapped, and either during this 95 wrapping operation or prior thereto the treated end 3 of the product is rolled or twisted to form a tip which is indicated by the numeral 5 and which conforms generally to the shape of the ordinary cigar 100 tip, the wrapping 4 being similarly formed about this end of the said product.

The next step in the method consists in applying to the article which is produced by the preceding step and which is clearly 105 illustrated in Fig. 4, an outside wrapping 6 of leaf tobacco of a high grade, this wrapping being applied by hand or by any approved type of machine in the manner usually followed in the manufacture of cigars 110 and completely covering the wrapping 4 previously applied.

By the method above recited, there is produced a cigar comprising a filler of tobacco in short or small pieces enclosed within a wrapping or envelope of paper and which in turn is enclosed in intermediate and outer wrappings of leaf tobacco respectively of relatively inferior and superior grades. It will be obvious that a cigar may be produced by this method at a much lower cost than by the ordinary methods and that while the filler 1 may be of a relatively high grade of tobacco it is much less expensive than a long filler owing to the fact that it is in small pieces.

It will be understood that by the method embodying the present invention, cigars may be manufactured in any size and shape desired whereas by methods previously followed the number of different sizes have been somewhat limited.

Having thus described the invention, what is claimed as new is:

1. The method of manufacturing a cigar which comprises preparing a paperwrapped

filler of fine cut tobacco, removing a portion of one end of the filler, and applying to the filler a wrapper of leaf tobacco and forming the said end of the filler.

2. The method of manufacturing a cigar which comprises wrapping a selected quantity of fine cut tobacco in paper into tubular form, removing a portion of the filler from one end thereof, and shaping the said end to form a tip and applying to the filler a wrapper of leaf tobacco.

3. As a new article of manufacture, a cigar comprising a filler of relatively small pieces of tobacco, a paper wrapper enclosing the filler, a portion of the particles of the filler at one end being removed and the paper wrapper being formed with a tip at said end, a wrapper of leaf tobacco of one quality enveloping the paper wrapper of the filler, and a wrapper of tobacco of a superior quality enveloping the whole.

In testimony whereof I affix my signature.

FRANCISCO ESPAILLAT DE LA MOTA. [L. S.]
